UNITED STATES PATENT OFFICE.

JOHN YOUNG, OF TIFFIN, OHIO.

HOSE-COUPING AND HYDRANT ATTACHMENT.

SPECIFICATION forming part of Letters Patent No. 341,713, dated May 11, 1886.

Application filed January 9, 1886. Serial No. 188,085. (No model.)

To all whom it may concern:

Be it known that I, JOHN YOUNG, of the city of Tiffin, in the county of Seneca and State of Ohio, have invented and claim a new and useful Hose Coupling and Hydrant-Attachment Device, of which the following is a specification.

The object and purpose of my invention are to make hydrant connections and attachments and also couple hose without the usual thread-cut or screw attachment, as shown in Figure 1, which is a perspective view of the device as applied to a hydrant. Fig. 2 shows the fastening in connection with two lengths of 15 hose and uncoupled. Fig. 3 shows a sectional view. Fig. 4 shows the section of the improvement to be used as a hydrant attachment.

The invention relates particularly to that 20 class of hose and pipe couplings in which the meeting sections of a coupling are clamped together by a hook on one section engaging pins or studs on the other; and the invention consists in certain features of construction 25 and combinations of parts, as will be herein-after described and claimed.

In the drawings, E E' designate the two sections of my coupling, each of which has a suitable portion, 1, which may be fitted in 30 and clamped to the lengths of hose. The section E is provided with a forwardly-projected nipple, C, and at the juncture of such nipple with the body of the section I form a groove, F, to receive the packing-ring D, which fits 35 and is usually held in said ring by its elasticity, being preferably formed of rubber. This section E also has lateral or radially-projected studs G. The section E' has its outer end formed with a mouth or enlarged 40 portion, 2, fitted to receive the nipple C, and at the inner end of this mouth I form a groove, F', in which is fitted the packing-ring D', similar to the ring D, before described.

To the section E' is pivoted the hook A, 45 formed preferably with arms A', connected by a cross-yoke comprising a loop, B, and a bar, I, arranged to be engaged by a pivoted button, H, in certain adjustments of the parts, in order to lock the sections coupled.

The loop B forms a convenient means by 50 which to suspend the hose while in use from a hook or nail on a ladder or other support, in connection with which the bar I and button H co-operate to prevent any disjoining of the hose when so supported. This button H 55 is pivoted at h on section E'.

In operation, to couple, the sections are 60 pressed together, as will be understood from Figs. 2 and 3, and the hook and button or latch H set to the position shown in Fig. 1. To uncouple, the reverse of the operation as 65 above described will be necessary.

It will be noticed that the packing-rings are so disposed that a double packing is provided for the joint, one at D and the other at 70 D', also that such packing-rings are held in place without separate fastening devices.

In operation, when the sections E E' are 75 clamped by the proper adjustment of the hook, the button H is turned so one of its ends will bear against the rear side of the bar which joins the hooked arms in such manner as to prevent any rearward movement of the bar and the arms it connects, so the hook cannot be freed until the latch is released. In this 80 arrangement the latch rests flat against the surface of the section and the strain thereon is exerted in the direction of its length, so that it cannot be bent out of the way.

By arranging the packing-ring D at the 85 juncture of nipple C with section E, and in a groove formed to receive it, even in case the inner joints of the sections should leak this will prevent the passage of the water.

What I claim is—

The improved hose-coupling herein described, consisting of the section E, having studs G, the section E', the hooks H, pivoted to section E', a bar, I, and loop B, connecting said hooks, the latter being adapted for use in suspending the hose, and the latch H, pivoted to the section E' and adjustable into engagement with the rear side of bar I, all substantially as and for the purposes specified.

JOHN YOUNG. [L. S.]

In presence of—

JAS. F. LEAHY,
L. G. COLE.
